UNITED STATES PATENT OFFICE.

WILLIAM H. HURLEY, OF NEW HAVEN, CONNECTICUT.

GAS-BURNER.

970,056.

Specification of Letters Patent. Patented Sept. 13, 1910.

Application filed February 23, 1909. Serial No. 479,428.

To all whom it may concern:

Be it known that I, WILLIAM H. HURLEY, a citizen of the United States, residing at New Haven, in the county of New Haven and State of Connecticut, have invented a new and useful Improvement in Gas-Burners; and I do hereby declare the following, when taken in connection with the accompanying drawings and the letters of reference marked thereon, to be a full, clear, and exact description of the same, and which said drawings constitute part of this specification, and represent, in—

Figure 1 a side view partially in section of a gas burner constructed in accordance with my invention. Fig. 2 a top or plan view of half of a burner with a portion of the deflector broken away.

This invention relates to an improvement in gas burners and especially to devices of a small character adapted to be applied to an ordinary gas bracket, the object being a simple arrangement of parts which will produce a blue flame; and the invention consists in the construction hereinafter described and particularly recited in the claim.

In carrying out my invention I employ a nipple 2 adapted to be applied to an ordinary gas fixture. In this nipple are a series of air inlet openings 3. Mounted upon the upper end of the nipple is a hollow head 4 forming a mixing chamber for air and gas. The head extends from the lower end upward so that the air and gas as it enters the head will have room to thoroughly mix. Extending outwardly and upwardly from the sides of this chamber are a series of

burner arms 5 more or less in number each provided with a burner tip 6 of usual form. 40 Mounted on the top of the head is a vertically arranged post 7 and secured to this post is a cone-shaped deflector 8. This may be held in place, as shown, by a nut 9. Mounted on the post 7 is a collar 10 upon 45 which rests a fan-wheel 11.

In use the gas from the fixture and the air entering the openings 3 are thoroughly mixed in the head 4 and pass from the chamber therein through the several arms 50 to the burners where the mixture may be ignited and the relative supply of air and gas is such as to produce a blue flame and hence avoid smoking. The heat from the burners is radiated by the deflector and the 55 hot air from the burners revolves the fan and thus maintains a current of air to the inside of the deflector.

I claim:—

A gas burner comprising a tube having 60 air openings, a hollow head or mixing chamber mounted on the upper end of said tube, said head round in transverse section, closed at its upper end and larger in diameter at its upper end than at its lower end 65 forming tapered sides, and a series of burner arms mounted in the sides of said head near the top and extending radially outward and then upwardly therefrom.

In testimony whereof, I have signed this 70 specification in the presence of two subscribing witnesses.

WILLIAM H. HURLEY.
